US00D692206S

(12) **United States Design Patent**
Slusarczyk et al.

(10) **Patent No.:** US D692,206 S
(45) **Date of Patent:** ** Oct. 29, 2013

(54) **TWISTED PET TREAT**

(74) *Attorney, Agent, or Firm* — Arent Fox LLP

(75) Inventors: **Peter Sebastian Slusarczyk**, Nolensville, TN (US); **Jonathan Christopher Smith**, Nashville, TN (US); **Vinod Gumudavelli**, Hermitage, TN (US); **Justin Tan Nguyen**, Nashville, TN (US)

(57) **CLAIM**

The ornamental design for a twisted pet treat, as shown and described.

(73) Assignee: **Mars, Incorporated**, McLean, VA (US)

DESCRIPTION

(**) Term: **14 Years**

(21) Appl. No.: **29/425,471**

(22) Filed: **Jun. 22, 2012**

FIG. 1 is a perspective view of a twisted pet treat showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1;

FIG. 8 is a perspective view of a second embodiment of a twisted pet treat showing our new design;

FIG. 9 is a front view of the design shown in FIG. 8;

FIG. 10 is a rear view of the design shown in FIG. 8;

FIG. 11 is a left side view of the design shown in FIG. 8;

FIG. 12 is a right side view of the design shown in FIG. 8;

FIG. 13 is a top view of the design shown in FIG. 8;

FIG. 14 is a bottom view of the design shown in FIG. 8;

FIG. 15 is a perspective view of a third embodiment of a twisted pet treat showing our new design;

FIG. 16 is a front view of the design shown in FIG. 15;

FIG. 17 is a rear view of the design shown in FIG. 15;

FIG. 18 is a left side view of the design shown in FIG. 15;

FIG. 19 is a right side view of the design shown in FIG. 15;

FIG. 20 is a top view of the design shown in FIG. 15; and,

FIG. 21 is a bottom view of the design shown in FIG. 15.
